[57] ABSTRACT

The truck, which is mounted for horizontal movement on a plurality of casters, includes an upright cabinet, and a pair of spaced, parallel, bowl-supporting arms which project horizontally out of a pair of vertical slots in the front wall of the cabinet. The arms can be elevated or lowered, selectively, by a hydraulic mechanism mounted in the cabinet. At their free ends the arms carry adjustably mounted bowl supports, which, when the arms are elevated, engage the handles at opposite sides of a mixing bowl to support the bowl releasably on the arms, and which automatically become disengaged from the bowl handles, when the arms are lowered to deposit the bowl on a surface. Manually operable means is provided for tipping the bowl for pouring its contents, while the bowl is supported on the arms.

FIG. I

3 FIG. 2

FIG. 3

FIG. 4

FIG. 5

MIXING BOWL LIFT TRUCK

This invention relates to mobile lift trucks, and more particularly to a truck having novel bowl lifting means thereon for picking up and transporting large mixing bowls in commercial kitchens, and the like.

It is quite common for the cooks of most commercial or institutional kitchens to use large, stainless steel mixing bowls, which may have anywhere from **12** to **60** quart capacities, for example. Even when empty these bowls often weigh as much as **25** pounds; and when filled may weigh upwardly from **75** to **100** pounds or more.

Because of their excessive weight and size, as compared, for example to conventional bowls, these large, commercial mixing bowls are difficult to manipulate. To simplify their handling, it has been proposed to employ simple trucks for conveying them about a kitchen or the like. Moreover, in view of the fact that the loaded bowls are so heavy, it has been proposed also to employ separate bowl handling devices for elevating and/or dumping the bowls. The disadvantage of these trucks and handling devices is that one is difficult to use with the other, unless they are specifically designed to cooperate with one another. Even then, such prior equipment has the disadvantage that the truck device must be used to convey bowls to and from the bowl handling device, so that the utility of the latter is extremely limited.

It is an object of this invention, therefore, to provide a novel lift truck, which is particularly adapted to elevate and convey commercial mixing bowls in commercial or institutional kitchens, and the like.

Another object of this invention is to provide novel bowl handling means, which is mounted on a mobile platform or truck so as to be readily movable between various working stations in a kitchen.

Still another object of this invention is to provide for a lift truck of the type described, novel bowl supporting means, which is engageable with the handles of standard commercial mixing bowls releasably and securely to support the bowls on the truck during movement thereby.

Other objects of the invention will be apparent hereinafter from the specification and from the recital of the appended claims, particularly when read in conjunction with the accompanying drawings.

In the drawings:

FIG. 1 is a plan view of a mixing bowl lift truck made according to one embodiment of this invention, with part of the truck being broken away and shown in section, and illustrating in broken lines a conventional mixing bowl mounted on the truck;

FIG. 2 is a front elevational view of this truck with a mixing bowl again being shown thereon by broken lines;

FIG. 3 is a sectional view taken generally along the line 3-3 in FIG. 2 looking in the direction of the arrows, and with part of one of the bowl supporting arms being broken away;

FIG. 4 is a side elevational view of the truck; and

FIG. 5 is an enlarged, fragmentary sectional view taken along the line 5-5 in FIG. 4 looking in the direction of the arrows.

Referring now to the drawings by numerals of reference, **10** denotes generally a lift truck comprising an upright cabinet **11** having thereon a removable cover **12**, and having a plane bottom **13** (FIG. 3) supported

adjacent opposite ends thereof on a pair of conventional casters **14**. Two, spaced, parallel legs **16**, which project forwardly from the face of cabinet **11**, are also supported at their outer ends on another pair of casters **18**.

Mounted in the cabinet **11** is a hydraulic cylinder **20** (FIGS. 1 and 3), the lower, closed end of which is connected to a clevis bracket **21**, which is secured to the bottom **13** of the cabinet. Cylinder **20** contains a telescopic piston rod **23** (FIG. 3), which projects out of the upper end of the cylinder. Rotatably mounted on another clevis or yoke **24**, which is fastened to the upper end of the piston rod **23**, is a pulley **26**. A cable **27**, which passes around the pulley **26**, is fastened at one end **28** to the bottom of the cabinet **11** adjacent its rear wall, and at its opposite end **29** is connected to a horizontal bar **31**, which is movable vertically in the cabinet **11** as noted hereinafter.

Opposite ends of the bar **31** are secured to the rear or inner ends of two, spaced, parallel bowl lifting arms **32** and **33**, which project slidably through a pair of spaced, vertical slots **34** and **35** (FIGS. 2 and 3) in the front wall of cabinet **11**. Rotatably mounted on the arms **32** and **33** adjacent their inner ends are two, identical guide rollers **36**, only one of which is shown in FIG. 3. Rollers **36** project outwardly from the arms into the grooved faces of a pair of vertical channels or guide tracks **38** and **39**, which are secured in cabinet **11** rearwardly of its front wall. Arms **32** and **33** are supported horizontally and in cantilever fashion on tracks **38** and **39** by a pair of diagonal braces **40** and **41** (FIGS. 1 to 4), which are welded or otherwise secured at their outer ends to the upper surfaces of arms **32** and **33**, and which project diagonally rearwardly into the cabinet **11** through the slots **34** and **35**. Rotatably mounted on the rear ends of the braces **40** and **41**, and projecting slidably and rotatably into the grooved surfaces of the vertical guide tracks **38** and **39**, are two other, identical guide rollers **42** (FIGS. 1 and 3).

Removably and adjustably mounted on the insides of the arms **32** and **33** adjacent their outer ends are two, similarly-shaped bowl supports **44** and **45**, respectively. As shown in greater detail in FIG. 5, support **45** comprises a rectangular base section **46** having in its upper surface a slot **47** for accommodating the hand grip portion **H'** of one of the two handles **H** on a conventional, commercial mixing bowl of the type illustrated in broken lines at **B** in FIGS. 1, 2, 4 and 5. Projecting from the face of the base section **46** is an integral leg **47**, which carries at its outer end an upright, arcuate flange **48**. This flange is adapted to engage the outside of the bowl **B**, and to project beneath the rolled lip which surrounds the open end of the bowl, when the latter is supported on truck **10** as shown in the drawings.

The support **45** is removably and pivotally mounted on the arm **33** by a bolt **51** (FIGS. 3 and 5) having a shank which projects slidably through a bore **52** in the base section, and through a washer or spacer **53** into a registering bore **54** in the arm **33**. A cap nut **55** is threaded on the outer end of the bolt **51** to draw its head against section **46**, but also to permit the support **45** to pivot about the bolt **51** as noted hereinafter.

Mounted on the outside of arm **32** adjacent its outer end is a conventional self-locking, quick-acting worm and gear unit **60** (FIGS. 1 and 2). This unit has an output shaft **61**, which projects rotatably through a registering opening in the arm **32**, and which is releasably

fastened to the base section 46 of the other bowl support 44 to mount support 44 for pivotal movement about the same axis as the support 45. Projecting from the outer surface of the unit 60 is a crank 62, which can be manually rotated to effect corresponding rotation of the shaft 61 upon which the support 44 is mounted. The self-locking feature of the unit 60 prevents rotation of the shaft 61 except by the crank 62.

To supply fluid under pressure for the cylinder 20, a conventional hydraulic pump 65 (FIG. 1) is mounted 10 in the cabinet 11 adjacent the cylinder 20 for operation by a foot pedal 66, which projects out of a slot in the rear wall of the cabinet 11 adjacent the lower end thereof. The pump 65 is connected in known manner to the lower end of the cylinder 20, so that when the pump 65 is operated by the foot pedal 66, fluid under pressure is forced into the lower end of the cylinder 20 thereby causing its piston 23 to project out of the upper end of the cylinder to force the overlying cable 27 upwardly in the cabinet 11. This causes end 29 at the 20 cable to draw the bar 31, and hence the arms 32 and 33 upwardly, the vertical motion of the arms being guided by the travel of the rollers 36 and 42 in the channels or tracks 38 and 39. To lower the arms 32 and 33 a manually operable switch 67 on the rear of the cabinet 11 is connected in any known manner, either mechanically or electrically to a conventional control valve, which allows fluid under pressure in the cylinder 22 to be returned to the system sump, which supplies fluid to the pump 65 in known manner. When switch 67 is operated to open the control valve, it enables the retraction of the piston rod 23, and the lowering of the arms 32 and 33.

In use, truck 10 is pushed manually about by means of a handle 68, which extends between a pair of brackets 69 that projects from the rear of cabinet 11. To pick up a bowl B from a table, for example, the truck is manipulated until its two arms 32 and 33 flank opposite sides of the bowl, with the supports 44 and 45 positioned beneath the bowl handles H. The pump 65 is then operated by manipulating the foot pedal 66 to cause the piston rod 23 to advance and elevate the arms 32 and 33 sufficiently to cause the supports 44 and 45 to pass their flanges 48 upwardly through the openings in the handles H and into engagement with the underside of the rolled lip on the bowl as illustrated, for example, in FIG. 2. This movement causes the handgrip portions H' of the handles to seat in the slots 47 formed in the upper ends of the base sections 46 of the supports (FIG. 5). The arms 32 and 33 are elevated far enough to lift the bowl off of the table after which the truck 10 can be manipulated to convey the bowl to, for example, a conventional mixer of the commercial variety.

This type of mixer usually has a bifurcated support which passes around the bowl and beneath a supporting rib 70 (FIG. 5) on the bowl, when the latter is positioned properly at the mixer. The switch 67 may then be operated to release hydraulic fluid from the lower end of cylinder 20 so that arms 32 and 33, and hence bowl B, will be allowed to drop far enough to enable the bowl rib 70 to become seated on the bifurcated support (not illustrated) on the mixer. Thereafter the arms 32 and 33 continue to drop until the supports 44 and 45 pass below, and become completely disengaged from the handles H on the bowl. Thereafter the truck 10 may be backed off from the mixer, leaving the bowl

B positioned on the mixer support beneath the associated beater, and permitting the truck to be used to manipulate other bowls if necessary, while the contents of the bowl previously deposited at the mixer are being blended. When the mixing operation is complete, the truck 10 can again be used to elevate the bowl from the mixer support and to convey the bowl to another station in the kitchen.

Whenever it is necessary to empty the contents of the bowl B, while the bowl is mounted on the truck 10, the operator need only to rotate the crank handle 62 to cause the support 44 to be swung about its pivotal axis. This pivotal motion is also imparted to the bowl B, and by the bowl to the other pivotal support 45, which thus allows the bowl to be swung manually into and out of pouring positions.

From the foregoing it will be apparent that the instant invention will considerably reduce the effort heretofore required to manipulate heavy mixing bowls of the type described. By combining the truck and bowl elevating features into a single unit, substantial savings in time and expense are achieved, as compared to prior devices. The truck 10 is extremely simple to operate, since the special bowl supports 44 and 45 automatically engage and disengage the bowl handles when the arms 32 and 33 are elevated and lowered respectively. Moreover by employing differently sized spacers 53 the distance between the supports 44 and 45 can be readily adjusted to adapt the unit for use with differently sized mixing bowls. Also, the gear unit 60 enables a loaded bowl to be tilted or pivoted on the arms 32 and 33 for pouring purposes, and without having first to remove the bowl from the truck.

While only a single embodiment of the invention has been illustrated and described in detail herein, it will be apparent that this application is intended to cover any modification thereof as may be apparent to one skilled in the art, and which may fall within the scope of the appended claims.

Having thus described my invention, what I claim is:

1. A lift truck for transporting a mixing bowl of the type having a pair of handles projecting from diametrically opposite sides thereof, comprising

a housing,

a pair of spaced legs attached to, and projecting forwardly beyond the front of, said housing, a plurality of wheels supporting said housing and its legs for movement into and out of an operative position in which a mixing bowl registers with the space between said legs,

a pair of spaced, parallel, vertically movable arms projecting in cantilever fashion forwardly from said housing above said legs to flank opposite sides of a bowl, when said housing is in said operative position,

a pair of spaced, confronting supports mounted for pivotal movement on said arms adjacent the outer ends thereof and positioned to be elevated by said arms releasably into engagement with a pair of handles projecting from diametrically opposite sides of said bowl, thereby to support the bowl releasably between said arms,

drive means in said housing connected to said arms for selectively raising and lowering said arms to raise and lower, respectively, said bowl relative to said housing, when the bowl is supported between said arms,

said supports being pivotal about a common axis located forwardly of said housing and extending transverse to said arms, and
 manually operable means for tilting said supports, and the bowl supported thereby, about said axis to enable the contents of said bowl to be poured while the bowl is supported between said arms each of said supports having thereon a pair of vertically disposed projections defining therebetween a slot, each pair of said projections being located in 10 spaced, confronting relation to a corresponding pair of projections on the other support, the vertical projections on said supports being positioned to pass around opposite sides of a bowl and beneath the handles thereon, when said housing is wheeled into operative relation with respect to a bowl, whereby upon elevation of said arms, said supports move upwardly into engagement with the bowl handles to support the bowl on said arms, whereby the handles become seated in said slots, one of said 20 vertical projections of each pair of projections on said supports being positioned simultaneously to engage in openings in the handles on said bowl, when said arms are elevated, and to become disengaged from said openings in said handles, when 25 said arms are lowered.

2. A lift truck as defined in claim 1, including means for adjustably attaching said supports to said arms to adjust the space between said vertical projections in accordance with the diameter of the bowls to be supported by said arms. 30

3. A lift truck as defined in claim 1, wherein said drive means comprises
 a hydraulic cylinder in said housing,
 a pump for supplying fluid under pressure to said cylinder, 35
 a retractable piston rod projecting from one end of said cylinder, and
 means connecting said rod to said arms to elevate and lower said arms when said fluid is supplied to 40 and discharged from, respectively, said cylinder.

4. A lift truck for transporting a mixing bowl of the type having a pair of handles projecting from diametrically opposite sides thereof, comprising

a housing, 45
 a pair of spaced legs attached to, and projecting forwardly beyond the front of said housing,
 a plurality of wheels supporting said housing and its legs for movement into and out of an operative position in which a mixing bowl registers with the 50 space between said legs,
 a pair of spaced, parallel, vertically movable arms projecting in cantilever fashion forwardly from said housing above said legs to flank opposite sides of a bowl, when said housing is in said operative position, 55
 a pair of spaced, confronting supports mounted for pivotal movement on said arms adjacent the outer ends thereof and positioned to be elevated by said arms releasably into engagement with a pair of handles projecting from diametrically opposite sides of said bowl, thereby to support the bowl releasably between said arms, 60

drive means in said housing connected to said arms for selectively raising and lowering said arms to raise and lower, respectively, said bowl relative to said housing, when the bowl is supported between said arms,

said supports being pivotal about a common axis located forwardly of said housing and extending transverse to said arms, and
 manually operable means for tilting said supports, and the bowl supported thereby, about said axis to enable the contents of said bowl to be poured while the bowl is supported between said arms, wherein said supports further comprising a pair of blocks releasably secured to the inside surfaces of said arms, and each of said blocks having a slot in its upper surface for accommodating the handgrip portion of the bowl handle and a vertical projection spaced from said slot which extends into an opening in the last-named handle upon movement of said supports into engagement with said handles to prevent the supported bowl from pivoting relative to the supports during tilting.

5. A lift truck as defined in claim 4, including means mounting said blocks on said arms for pivotal movement about a common axis extending at right angles to said arms, and
 crank-operated means on one of said arms connected to one of said blocks and operable to pivot the last-named block about said axis thereby to tilt a bowl mounted on said supports to pour out the contents of the bowl.

6. A lift truck for transporting a mixing bowl of the type having a pair of handgrips projecting from opposite sides thereof, comprising
 a mobile housing supported on wheels for movement into and out of operative relation to a mixing bowl, a pair of stationary, vertical tracks mounted in said housing,
 a pair of spaced, parallel arms mounted at their inner ends on said tracks for vertical movement thereon, and projecting in cantilever fashion horizontally out of a pair of vertical slots in said housing to flank a mixing bowl disposed in operative relation to the housing,

drive means in said housing connected to said arms and operable selectively to raise and lower said arms in unison,
 a pair of bowl supports removably and adjustably mounted on the outer ends of said arms and disposed to engage said bowl at diametrically opposite sides thereof to lift the bowl, when said arms are elevated, and automatically to lower and disengage said bowl, when said arms are lowered,
 means for adjusting the lateral spacing of said supports relative to their respective arms to enable use of the truck with bowls of different size, and
 means mounting said supports on said arms for pivotal movement about a common axis to enable tilting and pouring of a bowl mounted on said supports,
 each of said supports having in its upper surface a slot for accomodating one of said handgrips.
